UNITED STATES PATENT OFFICE.

EDWIN P. BENSON, OF NEW YORK, N. Y.

BINDER.

Application filed April 10, 1923. Serial No. 631,124.

To all whom it may concern:

Be it known that I, EDWIN P. BENSON, a citizen of the United States, residing at New York, in the county of New York and State 5 of New York, have invented certain new and useful Improvements in Binders, of which the following is a specification.

This invention relates to binders and has particular reference to one adapted to enclose 10 a replaceable filler such as a block of memora- randa sheets fastened together to form a filler.

An object of the invention is to provide means whereby the filler may quickly and 15 easily be inserted into and removed from the binder.

Another object is to provide means whereby the filler is securely held in place within the binder although readily applicable 20 thereto and removable therefrom.

A still further object is to provide a filler gripping member which permits the achievement of the above named objects while being at the same time economical to manufacture.

25 The invention is illustrated in the drawings of which—

Figure 1 is a perspective view of a binder with filler inserted;

Figure 2 is a partial plan view of the 30 binder and filler showing the filler gripping member;

Figure 3 is a transverse section through the filler gripping device and the binder; and

Figure 4 is a partial perspective of the 35 binder showing the end of the filler gripping member into which the filler is introduced.

It is of course clear that the form of the 40 invention shown is only a preferred one of many in which it may be embodied for practical use and yet employ the same inventive principle. It is also clear that the particular construction and arrangement of the parts and the character of the materials used 45 is generally immaterial so that various modifications in the form and design and character of the device may be made to satisfy the commercial trade without necessarily departing from the spirit of the invention.

In the preferred form shown in the drawings the invention relates to the use of a binder back 10 and cover members 11 and 12 between which a removable filler or memora- randa pad 13 is to be replaceably fastened. 55 In practically every form in which they are supplied these pads are bound near an edge such as 14 by binding members such as staples 15. Therefore on the upper and lower surfaces of the pad or filler near the bound 60 end these elements form a series of projections or protuberances. This condition is taken advantage of in the following manner.

The filler is held to the back 10 by the engagement therewith of a gripping member which in the form shown is a U-shaped channel plate 16 having limbs 17 and 18 converging or tapering toward each other at their outer ends. The plate 16 is fastened to the back 10 by any suitable means such as 70 rivets 19. At one end, each of the plates 17 and 18 are flared out as shown at 20 and 21 to facilitate the insertion of the filler.

In order more effectively to avail myself 75 of the projections 15 on the filler 13 whereby they may be made to assist in holding the filler in place on the binder I prefer to bend back the outer edges of the limbs 17 and 18 as shown at 22 and 23 to form a rib or shoulder back of which lie the projections on the 80 filler so that the filler is effectively held from slipping out of the gripping element 16 and can only be removed by slipping the filler laterally out of the gripping element. This gripping member with the limbs 17 and 85 18 and ribs 22 and 23 is formed of one piece of material so that the economy of its manufacture is greatly enhanced.

I claim:

A filler gripping member which includes a 90 channel plate having limbs to engage a filler, and integrally formed right angular projections on the inner faces of the limbs, projections on the bound end surfaces of the 95 filler to be directly engaged against the right angular projections on the limbs.

In testimony whereof I affix my signature.

EDWIN P. BENSON.
